CLAIM

The ornamental design for a junction box for solar panel as shown and described.

DESCRIPTION

FIG. 1 is a left view of a junction box for solar panel showing our new design;

FIG. 2 is a front view thereof;

FIG. 3 is a top view thereof;

FIG. 4 is a perspective view thereof;

FIG. 5 is a bottom view thereof;

FIG. 6 is a back view thereof;

FIG. 7 is a right view thereof;

FIG. 8 is another perspective view thereof; and,

FIG. 9 is yet another perspective view thereof.

The parts shown by means of broken lines in the reproductions are not part of the claimed design.
